UNITED STATES PATENT OFFICE.

CARL A. CARLSON, OF BARBERTON, OHIO, ASSIGNOR TO THE DIAMOND MATCH COMPANY, OF CHICAGO, ILLINOIS, A CORPORATION OF ILLINOIS.

MACHINE FOR MAKING CARD-MATCHES.

1,132,302.

Specification of Letters Patent. Patented Mar. 16, 1915.

Application filed November 22, 1913. Serial No. 802,375.

To all whom it may concern:

Be it known that I, CARL A. CARLSON, a citizen of the United States, and resident of Barberton, in the county of Summit and 5 State of Ohio, have invented certain new and useful Improvements in Machines for Making Card-Matches, of which the following is a specification.

This invention relates to a machine for 10 making card matches, more especially those that are adapted to be secured within a book-like cover; my object being to provide a machine whereby such matches can be rapidly and efficiently produced.

15 In the embodiment of the invention herein illustrated match stock, such as paper or strawboard, is drawn from a suitable roll and fed to mechanisms whereby blanks are severed successively from the stock and each 20 succeeding blank formed with two rows of oppositely-extending alternately-staggered splints having a common connecting portion, and whereby the card thus formed is folded longitudinally of the connecting portion and 25 transferred to a suitable carrier by means of which the card is transported through the usual dipping and drying path.

The invention comprises various novel 30 features of construction and combinations 35 of parts which will be hereinafter described and claimed; it being understood that while I shall point out the details of the mechanism illustrated, I do not restrict myself thereto as the apparatus may be variously modified without departing from the spirit 40 of the invention.

In the drawings—Figure 1 is a longitudinal vertical section on a plane through the feed rolls for the match stock, the die and 45 setting plungers, and their adjuncts, and a portion of the endless carrier for the match cards. Fig. 2 is a transverse vertical section, as on the line 2—2 of Fig. 1, the head of the setting plunger being partly broken away to expose a die member of the die plunger. Fig. 3 is a horizontal section, as on the line 50 3—3 of Fig. 1. Fig. 4 is a side elevation of a portion of the machine showing the mechanism for actuating the carrier. Fig. 5 is a plan, enlarged, of one side of a portion of the carrier, showing more clearly the connections for the clamp bearing bars. Fig. 6 is a longitudinal section through a portion 55 of the carrier with folded match cards therein, the head of the setting plunger be-

ing shown at the limit of its active stroke. Fig. 7 is a plan of the match card just before it is folded and set in the carrier. Fig. 8 is an edge view of said card.

11 is a suitable supporting frame; and 12 60 a drive shaft journaled in bearings in said frame.

13, 14 are upper and lower vertical guide brackets bolted to the frame; and 15 is a vertically reciprocating plunger, termed a 65 "die plunger", mounted to slide in and between said guide brackets. This plunger comprises two parallel sections united at their lower ends, as by bolts 16, and spaced to provide a vertical guide-way for a supplementary plunger 17 termed the "setting plunger", having a laterally reduced or beveled upper end portion 170. The die plunger is provided at its lower end with 70 anti-friction rollers 18 which run in corresponding cam-ways 19 in two suitably-spaced face cams 20 fast on the drive shaft, and the setting plunger 17 is also provided at its lower end with anti-friction rollers 21 75 which run in cam-ways 22 in the same cams. 80 The contours of the respective cam-ways 19, 22 are such that during the rotation of the cams the two plungers are independently reciprocated in a certain operative relation to each other in order to perform their respective functions, as will presently appear.

Fast on the upper ends of the plunger sections 15 are two corresponding die members 23, each of which comprises a bar transversely grooved on its upper surface to provide a series of alternating ribs 24 and recesses 25, each equal in width, or substantially so, to the width of a match. The upper surfaces of the ribs are inclined as indicated, and the die members are spaced to 90 permit the free vertical movement between them of the supplementary plunger 17.

Bolted to the guide brackets 13 are two die members 26 which overhang and are complementary to the die members 23, that is to say, the upper members are provided on their under sides with alternating ribs 27 and recesses 28 which are constructed and arranged to register with the opposing recesses and ribs respectively of the lower die members when the latter are raised by actuation of the plunger. The lower or functional surfaces of the ribs 27 are reversely inclined to the opposing surfaces of the ribs 24. Thus, if a sheet of match stock, such as 110

card board, be interposed between the upper and lower dies and the dies be relatively moved into registry, the card will be slitted by the co-acting edges of the respective upper and lower ribs in a manner to produce two rows of match splints with a common connecting portion along the middle of the card, the alternate splints, by virtue of the inclined faces of the ribs, being deflected laterally, or "staggered," to facilitate the subsequent dipping or "heading" of the free ends of the splints. (See Figs. 1, 7 and 8). The walls of the throat of the upper die members 26 are provided with a series of vertical recesses 29 corresponding with and opening into the recesses 28, said vertical recesses being adapted to permit the free upward passage of the alternate laterally-projecting match splints of the card when the latter is being acted upon by the setting plunger as will now be described.

The contours of the cam-ways are such that during each rotation of the drive shaft the die plunger 15 is raised through the agency of the ways 19 to force the lower dies into registry with the fixed upper dies (for the formation of the connected rows of match splints as above described) and then lowered and maintained at rest for an interval; and the setting plunger, immediately upon the lowering of the plunger 15, is raised by the action of the cam-ways 22 and then lowered and maintained at rest for an interval. In its upward stroke the head portion of the setting plunger contacts with the opposing uncut median part of the match card and forces the latter bodily upwardly within and through the recessed throat of the upper die-members, thus positively folding the match card upon the head of the plunger 17. Upon the descent of the setting plunger the several parts are in position for a succeeding operation. A suitable carrier is mounted to travel across the path of the ascending setting plunger in a plane above the dies, which carrier is constructed to receive and grip the folded portion of the match card as the plunger reaches the limit of its upward stroke and before its descent. This carrier receives the successively formed match cards and transports them through the match making path, wherein the free extremities of the splints are supplied with paraffin and ignition composition. In the present instance the carrier comprises an endless chain of parallel bars 30 provided with co-acting spring-clips 31 which are arranged to receive and clamp the folded edges of the successive cards. The bodies of the bars are rectangular in cross-section, and the clips embrace the respective bars and are secured thereto by the bottom clamp pieces 32. These bars are arranged to provide unitary sections, comprising each several bars secured together by

suitably-disposed locking members 33 beyond which are extended the free ends of the bars. These extended ends are cylindrical. The adjoining sections are pivotally connected by links 34 which are slipped upon the ends of the adjacent bars of the sections, and are held in place thereon by the overlapping of the links by the shouldered ends of perforated members 35 which are slid upon and secured to the bars of the respective sections. The members 35 and links 34 constitute, in effect, a continuous bearing surface which, in the travel of the flexible carrier passes and rests upon a horizontal supporting ledge 36 on the main frame. The extended ends of the bars are uniformly spaced for engagement by the teeth of actuating gear wheels 37 on a transverse shaft 38, which is intermittently actuated in any suitable manner in order to effect the requisite step-by-step movement of the carrier, as will be hereinafter described.

Although the match card blanks may be previously prepared and fed to and between the die members, yet I prefer to supply the material progressively thereto from a suitable roll of stock, and to sever card blanks from the infed material during the operation of the die mechanism. In the drawings I have illustrated the feeding and cutting mechanism as follows: 39 is a suitably-disposed horizontal bed along which the match material 40 is fed to and between the die-members by means of a pair of intermittently rotatable feed rolls 41. The shafts of these rolls are journaled in suitable bearings 42 slidingly fitted to brackets 43 on the main frame. The upper brackets are normally depressed by suitably-disposed springs 430 (one of which is indicated in Fig. 1) the force of which to insure efficient contact of the rolls with the interposed stock, may be nicely regulated by manipulating suitable adjusting screws 431 in the caps 432 of the brackets. One of the rolls is provided with equally spaced peripheral blades 44—(in the present instance three) and the other with a complementary groove 44a for the blades, which devices are positioned to score or crease the material transversely at intervals corresponding with the median fold lines of the successive cards (C), as indicated at Figs. 1, 3, 7 and 8.

Any suitable means for actuating the rolls may be employed. In the present instance the projecting ends of the roll shafts at one side of the machine are connected by meshing gear wheels 45. One of the shafts bears a ratchet wheel 46 with the teeth of which engages a spring-pressed dog 47 pivoted to a crank-disk 48 on the end of the roll shaft. This disk is connected by means of a pitman 49 with a gear wheel 50 turning on a stud on the side of the main frame, which wheel meshes with a gear wheel 51 on the main

shaft 12. During the continuous rotation of the latter the crank disk is oscillated by the pitman connection a peripheral distance equal to the complete length of the stock which is to be severed; and hence a corresponding intermittent motion is transmitted through the dog and ratchet mechanism, and the co-acting gear wheels, to the feed rolls. The gears are so proportioned that the upper roll makes three rotations to one of the lower roll in order that the blades of the latter will successively register with the peripheral groove of the upper roll.

15 Affixed to the rearward die bar 23 is an upwardly extending plate 52 which constitutes a determinate stop for the leading end of the match material when it is fed between the dies and severed; and secured to the forward die-bar 23 is an upwardly extending cutter blade 53 which, co-acting with a depending cutter blade 54 on the forward upper die, severs the interposed material transversely. The inner upper edge of the blade is beveled to a cutting edge, as at 55, the distance between the inner face of said blade and the stop being equal to the width of a match card. The material is fed by the feed rolls near to, but not into contact with the stop, so that when the proper quantity 30 of material is severed by the cutters 53, 54 the beveled edge of the blade 53 forces the blank against the stop in a manner to position the latter relatively to the dies and the setting plunger. The cutters are, of course, arranged to sever the material before the dies engage the latter.

40 The co-operative relation of the feeding and cutting devices is such that at the instant the blade 53 has severed the stock the dog 47 has started on its backward travel for reengagement with another tooth of the ratchet wheel. During this idle period of the feed rolls, the stock, being firmly pressed against the blade and being sufficiently rigid 45 to prevent buckling, acts as a brake or stop for the rolls.

45 The mechanism herein illustrated for intermittently rotating the carrier actuating shaft 38 is as follows. Fast on one end of the lower roll shaft is an eccentric 56 which is pivotally connected by means of a rod 57 with a crank disk 58 loose on the end of the shaft 38. This disk bears a spring-pressed dog 59 which engages the successive teeth of a ratchet wheel 60 fast on the shaft 38. (See Fig. 4.) During the rotation of the lower roll an oscillatory motion is transmitted to the crank disk and its dog by the rod 57, and hence the dog by its engagement with the opposing ratchet teeth effects the step-by-step movement of the shaft 38, and the latter in turn through its gear wheels 37 impels the carrier. In Fig. 4 the devices just described are represented at the limit of 55 their forward travel, in which case the car-

rier is positioned to receive a folded match card.

In order to obviate any liability of the folded match card being withdrawn from the carrier during the descent of the setting 70 plunger, the top of the upper die member is disposed slightly below the inserted match card. The alternate depending splints of the inserted card when they clear the throat of the dies spring outward over the top of 75 the latter which thus presents an efficient back stop to the splints. (See Figs. 1 and 6.)

I claim—

1. In a match making machine, the combination of mechanism for forming a match card having two rows of oppositely-extending splints with a common connecting portion, and means for folding the card longitudinally of the connecting portion, said means including a member which acts upon such connecting portion while the card is associated with the forming mechanism.

2. In a match making machine, the combination of mechanism for forming a match card having two rows of oppositely-extending splints with a common connecting portion, and means for ejecting the card from the said mechanism and at the same time folding the card longitudinally of the connecting portion.

3. In a match making machine, the combination of mechanism for forming a match card having two rows of oppositely-extending splints with a common connecting portion, a carrier, and means for folding the card longitudinally of the connecting portion and introducing the folded edge to the carrier.

4. In a match making machine, the combination of mechanism for scoring match stock, means for forming from said stock a match card having two rows of oppositely-extending splints with a medially-scored common connecting portion, a carrier, and means for folding the card along the score line and introducing the folded edge to the carrier.

5. In a match making machine, the combination of mechanism for feeding match stock, means for cutting the stock into match card blanks, means for cutting the successive blanks to form match cards each having two rows of oppositely-extending splints with a common connecting portion, a carrier, and means for folding the card medially of the connecting portion and introducing the folded edge to the carrier.

6. In a match making machine, the combination of mechanism for feeding and transversely scoring match stock, means for cutting the scored stock into match card blanks, means for cutting the successive blanks to form match cards each having two rows of oppositely-extending splints

- with a medially-scored common connecting portion, a carrier, and means for folding the card along the score line and introducing the folded edge to the carrier.
7. In a match making machine, the combination of upper and lower splint cutting dies movable relatively to each other to form a match card having two rows of oppositely-extending splints with a common connecting portion, and means movable transversely of the dies for folding the card longitudinally of the connecting portion.
8. In a match making machine, the combination of a carrier, upper and lower splint cutting dies movable relatively to each other to form a match card having two rows of oppositely-extending splints with a common connecting portion, and means movable transversely of the dies for folding the card longitudinally of the connecting portion and introducing the folded edge to the carrier.
9. In a match making machine, the combination of upper and lower splint cutting dies having alternating ribs and recesses and a transverse throat portion, said ribs being inclined as described and said throat portion having a series of lateral recesses corresponding with and opening into the recesses of the upper die, means for effecting relative movement between said upper and lower dies, and a folding member movable transversely of said dies and through the said throat portion.
10. In a match making machine, the combination of a carrier, upper and lower splint-cutting dies adjacent thereto having alternating ribs and recesses and a transverse throat portion, said ribs being inclined as described and said throat portion having a series of lateral recesses corresponding with and opening into the recesses of the upper die, means for effecting relative movement between said upper and lower dies, and a folding and setting member movable transversely of the dies and through said throat portion.
11. In a match making machine, the combination of upper and lower splint-cutting dies movable relatively to each other to form a match card having two rows of oppositely extending splints with a common connecting portion, said dies having a transverse passage way in the plane of the said connecting portion, and a reciprocable plunger movable into and through the said passage way adapted to fold the card longitudinally of the connecting portion.
12. In a match making machine, the combination of a carrier, upper and lower splint-cutting dies movable relatively to each other to form a match card having two rows of oppositely-extending splints with a common connecting portion, said dies having a transverse passage way in the plane of the said connecting portion, and a reciprocable plunger movable into and through the said passage way adapted to fold the card longitudinally of the connecting portion.
13. In a match making machine the combination of a fixed upper die, a complementary lower die therefor, means for reciprocating said lower die toward and from the upper die to produce a match card having two rows of oppositely-extending splints with a common connecting portion, said dies having a transverse passage therethrough in the plane of the said connecting portion, a plunger, and means for reciprocating said plunger through the said passage after the card has been formed and the dies separated.
14. In a match making machine, the combination of a plunger having a guide-way longitudinally thereof, splint-cutting die members on said plunger, stationary die members complementary to the die members on the plunger, a second plunger movable within and longitudinally of the said guide-way and transversely of the respective die members, said die members having spaces for the passage of the latter plunger, and means for periodically reciprocating the two plungers.
15. In a match making machine, the combination of a carrier, a plunger movable at right angles thereto having a guide-way longitudinally thereof, splint cutting die members on said plunger, stationary die members complementary to the die members on the plunger, a second plunger movable within and longitudinally of the said guide-way and transversely of the respective die members, said die members having spaces for the passage of the latter plunger, and means for periodically reciprocating the two plungers toward and from the carrier.
16. In a match making machine, the combination of a carrier, means for progressively advancing the same, a plunger movable at right angles to said carrier having a guide-way longitudinally of the plunger, splint-cutting die members on the plunger, a second plunger movable within and longitudinally of the said guide way and transversely of the respective die members, said die members having spaces for the passage of the latter plunger, means for periodically reciprocating the two plungers toward and from the carrier, means for periodically feeding match stock between the die members and across the path of the second plunger, and means for severing card blanks successively from the portion of the stock between the die members.
17. In a machine for making matches, a carrier embodying a chain of unitary sections comprising each a series of parallel bars secured together by locking members

beyond which extend the free ends of the bars, co-acting spring clips on said bars, links applied to the ends of the adjacent bars of adjoining sections, and perforated members on the bars of the respective sections overlapping the ends of said links.

5 Signed at Barberton in the county of

Summit and State of Ohio this 18th day of Nov. A. D. 1913.
